K. S. BAXTER.

DOOR LATCH.

APPLICATION FILED MAR. 18, 1920.

1,362,217.

Patented Dec. 14, 1920.

Inventor:
Kenneth S. Baxter

By *Kenneth S. Baxter*

UNITED STATES PATENT OFFICE.

KENNETH S. BAXTER, OF MICHIGAN CITY, INDIANA, ASSIGNOR TO SHEET STEEL PRODUCTS COMPANY, A CORPORATION OF INDIANA.

DOOR-LATCH.

1,362,217.

Specification of Letters Patent. Patented Dec. 14, 1920.

Application filed March 18, 1920. Serial No. 366,781.

To all whom it may concern:

Be it known that I, KENNETH S. BAXTER, a citizen of the United States, and resident of Michigan City, county of Laporte, and 5 State of Indiana, have invented certain new and useful Improvements in Door-Latches, of which the following is a specification, and which are illustrated in the accompanying drawings, forming a part thereof.

10 The invention relates to latches especially adapted for use on vehicle doors, and intended primarily to be applied to the doors of auto truck cabs. Truck cab doors are usually loosely fitted in their casings for the 15 reason that the distortion or weaving of the cab, due to uneven roads or other causes, tends to make the door bind at times if closely fitted. Such distortion also results in a variable spacing of the latch casing 20 from the door casing, and it therefore becomes necessary to employ a longer latching bolt than will serve in other situations. It is also desirable that the latching bolt be so formed that it will tend to draw the door 25 closely shut.

The object of the present invention is to provide a latch which will meet these various conditions and have other advantages, as hereinafter pointed out; and it consists 30 in a structure such as is hereinafter described and as illustrated in the accompanying drawings, in which—

Figure 1 is a detail elevation of the side wall and door of a truck cab with the latch 35 applied;

Fig. 2 is a top view of the door, the jamb being shown in section;

Fig. 3 is a sectional view on the line 3—3 of Fig. 2;

40 Figs. 4, 5 and 6 are sectional views on the lines, respectively, 4—4, 5—5 and 6—6 of Fig. 3.

The invention is shown in connection with a cab and its door formed of sheet metal, 45 though it may be employed where such structure is of wood.

A portion of the door casing or jamb is shown at 10, and of the door at 11, the door being provided with a marginal flange 12 50 adapted to overlap the casing 10.

The latch comprises a casing 13, adapted to be secured to the inner face of the door 11, as by means of screws. There is housed within the casing 13 a reciprocating bolt 14,

the end of which projects through a suitable aperture in the end of this casing, and to engage back of the inner face of the door jamb when the door is closed. The bolt 14 is normally held in advanced position by means of a spring, as 15, and is withdrawn 60 by means of a crank-arm 16, engageable in a suitable pocket or recess in the body of the bolt and carried by a spindle 17 journaled in the casing 13 and extending through the outer face of the door, suitable 65 handles, as 18, 19, being fixed upon the opposite ends of the spindle. The face of the nose of the bolt 14 which is adapted to engage the inner face of the door jamb is beveled, as shown at 20, thereby providing 70 a cam action on the jamb as the bolt is projected by the spring 15 for drawing the flange 12 snugly against the outer face of the jamb.

A detent 21, shown as taking the form 75 of a bolt, is adapted to engage a forwardly projecting shoulder 22 carried by the bolt while the latter is completely retracted. In the construction as shown the shoulder 22 is the end of a flange 23 projecting laterally 80 from the bolt 14, and which, when the detent 21 is withdrawn, slides within a lateral recess 24 in this detent. The detent 21 is slidingly mounted in a bracket 25, which may be riveted to a wall of the casing 13. 85 A spring 26, coiled about the detent 21, reacts between a shoulder 27 of the bracket 25 and a pin 28 set through the detent, and tends to withdraw the detent to bring its lateral recess 24 out of line with the flange 90 23, thereby bringing a solid portion of the detent in line with the shoulder 22. By this arrangement the bolt 14 is held in retracted position so long as the door remains open.

A trip 29 is pivoted within the casing 13, 95 and, as shown, to the bracket 25, one end of this trip bearing against the outer end of the detent 21 and its other end 30 projecting through the front edge of the door 10 within the flange 12. Upon the closing of 100 the door the end 30 of the trip engages the door jamb and is forced into the position shown in Fig. 5, its inner end moving the detent 21 in opposition to the spring 26, bringing its recess 24 into alignment with 105 the flange 23 and permitting the bolt 14 to be projected by the spring 15.

While a practical and efficient form of

construction is herein shown and described, I do not limit myself to this particular form, but claim as my invention—

1. In a door latch, in combination, a 5 spring-advanced reciprocable bolt having the back face of its nose beveled to engage a keeper for forcing the door to fully closed position by a cam action as the bolt is advanced by its spring, means for holding the 10 bolt in withdrawn position, and means actuated by contact with the door jamb as the door is closed for releasing the holding means.

2. The combination with a swinging door 15 and the door jamb of a spring advanced bolt normally projecting beyond the free edge of the door within the plane of the outer face of the door, means for retracting the bolt, means for holding the bolt in retracted position and means actuated by contact with the outer face of the door jamb after the bolt has passed beyond the plane 20 of the same for releasing the said holding means when the door is closed.

25 3. The combination with a swinging door and the door jamb of a spring advanced bolt normally projecting beyond the free edge of the door within the plane of the inner face of the door and having the back 30 face of its nose beveled to engage the inner face of the door jamb for forcing the door to fully closed position by a cam action as the bolt is advanced by its spring, means for retracting the bolt, means for holding 35 the bolt in retracted position and means actuated by contact with the outer face of the door jamb after the bolt has passed beyond the plane of the same for releasing the said holding means when the door is closed.

4. The combination with a swinging door 40 and the door jamb of a flange projecting from the free edge of the door in substantially the plane of the outer face of the door and overlapping the door jamb upon the outside of the same, a spring advanced bolt 45 normally projecting from the free edge of the door for engagement with the door jamb upon the inside of the same, means for retracting the bolt, means for holding the bolt in retracted position and means comprising a detent located under the said flange 50 actuated by contact with the door jamb upon the outside of the same for releasing the said holding means when the door is closed.

5. The combination with a swinging door 55 and the door jamb of a spring advanced bolt normally projecting from the free edge of the door for engagement with the door jamb upon the inside of the same, means for retracting the bolt, means for holding the bolt in retracted position and means actuated by contact with the door jamb upon the outside of the same for releasing the 60 said holding means when the door is closed.

6. The combination with a swinging door 65 and the door jamb of a spring advanced bolt normally projecting from the free edge of the door and having the back face of its nose beveled for forcing the door to fully closed position by cam engagement with the 70 door jamb upon the inside of the same as the bolt is advanced by its spring, means for retracting the bolt, means for holding the bolt in retracted position and means actuated by contact with the door jamb upon the outside of the same for releasing the said 75 holding means when the door is closed.

KENNETH S. BAXTER.
